SAFETY RAZOR BLADE SHARPENER

Filed Nov. 28, 1932

UNITED STATES PATENT OFFICE

1,972,954

SAFETY RAZOR BLADE SHARPENER

Basil H. Savage, San Diego, Calif., assignor to
 Savage Research Corporation, San Diego,
 Calif.

Application November 28, 1932, Serial No. 644,630

11 Claims. (Cl. 51—111)

My invention relates to safety razor blade sharpeners, and the objects of my invention are:

First, to provide a device of this class which is particularly compact, the enclosing case being 5 but slightly larger in diameter than the length of a razor blade;

Second, to provide a device of this class in which the razor blade may be readily and quickly placed therein or removed without danger to 10 one's fingers;

Third, to provide a device of this class in which the sharpening elements engage the blade with a wiping movement which is conducive to obtaining a keen edge;

15 Fourth, to provide a device of this class which operates on both sides of each edge of the blade;

Fifth, to provide a device of this class which is operated by the mere turning of a crank;

Sixth, to provide a device of this class which 20 incorporates a cupped casing having a latch means so arranged as to be released by the turning handle for opening the casing, the turning handle being arranged to fold against the casing when not in use;

25 Seventh, to provide a device of this class which may act upon blades of different thickness without adjustment;

Eighth, to provide a device of this class in which the honing or sharpening elements are shifted to 30 a concealed or out of the way position clear of the razor blade edge when the turning handle is shifted to a position for opening the casing, thus protecting the razor blade from improper engagement with the hones; and

35 Ninth, to provide on the whole a novelly constructed safety razor blade sharpener which is particularly simple and economical of manufacture, durable, efficient in its action, and which will not readily deteriorate or get out of order.

40 With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is a side elevational view of my safety 50 razor blade sharpener with the handle shown in its folded position; Fig. 2 is a plan view thereof with the handle shown extended to its operating position; Fig. 3 is a plan view thereof with the casing in its open position; Fig. 4 is a fragmentary sectional view through 4—4 of Fig. 3 show-

ing the shiftable razor blade clamping elements in its extended position assumed when the casing is open; Fig. 5 is a sectional view through 5—5 of Fig. 2 with parts and portions shown in elevation; Fig. 6 is a sectional view through 6—6 of Fig. 2 with parts and portions shown in elevation; Fig. 7 is a fragmentary sectional view through 7—7 of Fig. 5, also with parts and portions shown in elevation; and Fig. 8 is an enlarged sectional view through 8—8 of Fig. 6 showing in detail 65 the friction pin used to join the handle with the operating shaft.

Similar characters of reference refer to similar parts and portions throughout the several views of the drawing.

70 Casing members 1 and 2, hinge means 3, clip 4, razor blade clamp bars 5 and 6, screws 7, driving shaft 8, handle 9, pin 10, driven shaft 11, collars 12 and 13, hone supporting springs 14 and 15, hones 16, and coil spring 17, constitute the principal parts and portions of my novel safety razor blade sharpener.

75 The sharpener is enclosed in a pair of complementary casing members 1 and 2 which are preferably cup-shaped, relatively shallow, and polygonal in plan so as to provide a ready grip, particularly when one's hands are wet.

The two casing members are connected together by hinge means 3 at their one sides, and by a clasp means at their opposite sides. The 80 clasp means is mounted in alined recesses or channels 1a and 2a which together traverse the edge of the closed case formed by the casing members 1 and 2, respectively, as shown best in Figs. 2 and 6. The recess 1a is provided at the 85 inner side of its base wall or inner wall with a catch portion 1b. The corresponding wall of the recess 2a supports a spring clip or latch member 4 which extends downwardly or rather towards the casing 1 so as to engage the catch 1b when the two casings are brought into juxtaposition, as shown in Fig. 6. The clip 4 is provided with a knob 4a which protrudes into the recess 2a and is adapted to be engaged by the operating handle, as will be described herein- 90 after.

Extending diametrically across the two casings 1 and 2 in parallel relation with the axis of the hinge 3 are a pair of clamp bars 5 and 6 which are adapted to register with each other. The 105 clamp bar 5 is provided with end portions which are offset into the casing 1 and are secured thereto by means of screws 7. The intermediate portion of the clamp bar 5 extends substantially flush with the edge of the casing 1, and is provided 110

with upwardly projecting lugs 5a which are adapted to fit into the apertures formed in the conventional razor blade B, as shown best in Fig. 3. The clamp bar 6 is also provided with offset end portions which extend into the casing 2 and which are secured thereto by means of other screws 7. However, the movable clamp bar 6 is not rigidly secured but is capable of slight movement along the axis of these screws. 10 The intermediate portion of the movable clamp bar 6 is provided with apertures 6a which register with lugs 5a and receive their extremities, as shown in Figs. 3 and 5.

The clamp bar 5 is provided with a centrally disposed bearing 5b which extends axially into the casing 1. The bearing 5b receives a driving shaft 8 which extends through a bearing 1c provided in the crown of the casing 1. The protruding end of the driving shaft 8 pivotally supports 20 an arm 9a of a handle member 9. The connection between the shaft 8 and the arm 9a is effected by a pin 10 which is split or otherwise formed to provide frictional resistance to pivotal action of the arm 9a so that said arm tends to maintain any position to which it is moved. The arm 9a is curved so as to follow the curvature of the casing 1 when in its one extreme position as shown in Fig. 1 and by dotted lines in Fig. 6. The extremity of the arm 9a is provided with a 25 knob 9b which is adapted to fit into the recesses 1a and 2a, as shown best by the dotted line position of the handle indicated in Fig. 6. A portion of the knob 9b rests against the pin or projection 4a of the clip 4 so that inward pressure 30 upon the arm 9a or knob 9b causes the clip 4 to disengage the catch 1b.

The inner end of the shaft 8 terminates in a semi-cylindrical lug 8a which registers with a corresponding lug 11a of a driven shaft 11, the 40 two lugs forming a clutch mechanism for connecting the driving shaft 8 with the driven shaft 11. The driven shaft 11 extends through an axially disposed sleeve 6b formed in the shiftable clamp bar 6, and into a bearing 2c formed in the casing 2. The sleeve 6b is constricted at its secured 45 end so as to coat with a flange 11b surrounding the shaft 11, as shown best in Figs. 4 and 5, and limit inward movement of the shaft.

The extremities of the bearing 5b and the 50 sleeve 6b are spaced from the corresponding bearings 1c and 2c, in which spaces are mounted collars 12 and 13, respectively. The collars 12 and 13 rotate with their respective shafts, said shafts being flattened at opposite sides and the collars being correspondingly formed.

The collars 12 and 13 support leaf springs 14 and 15, respectively. The springs extend at first 55 radially and curve to conform to the crowns of the casing members, then double against themselves forming open loops and extend radially inwardly towards the axis of the shafts 8 and 11 and are apertured as indicated by 14a and 15a, respectively, so as to surround said shafts, then again extend radially and terminate in clip portions 14b and 15b, respectively, as shown best in Fig. 6. The clips 14b and 15b support cylindrical hone members 16, the exposed sides of which face towards the central portion of the casing so as to engage opposite sides of the razor blade B, as 70 shown best in Fig. 6.

Between the collar 13 and the flange 11b within the sleeve 6b there is mounted a coil spring 17. The spring 17 by action against the flange 11b tends to hold the clamp bar 6 in its extended 75 position against the heads of the screws 7, as

shown in Fig. 4, so that when the two casing members are brought together the clamp bar 6 is shifted to the position shown in Fig. 5 against the action of the spring 17, thereby firmly holding the razor blade as well as providing sufficient tension to 80 separate the casing members slightly when the clip 4 is disengaged from the catch 1b. The spring 17 also performs another function. Should the shafts 8 and 11 be shifted so that the lugs 8a and 11a do not register, the shaft 11 moves axially against the action of the spring 17 and remains disengaged from the shaft 8 until the handle 9 is turned sufficiently to bring the said lugs into registration, whereupon the shaft 11 85 snaps into interlocking relation with the shaft 8 and the two may be turned in unison.

In order to restrain the action of the springs 14 and 15 when there is no razor blade in the sharpener, the outer peripheries of the bearing 5b and sleeve 6b are provided with shoulders 5c and 6c, respectively, which engage the margins of the apertures 14a and 15a, respectively. The shoulders 5c and 6c are provided with cam portions 5d and 6d, respectively, which engage the margins of the apertures 14a and 15a as the hones pass 90 across the clamp members so as to depress the springs and cause said hones to clear said clamp members, as shown by dotted lines in Fig. 5.

The sharpener is operated as follows: The casing is opened as shown in Fig. 3 and the razor blade 105 is positioned on the clamp member 5. The casings are then closed and the handle 9 turned until the shafts 8 and 11 are connected; whereupon continued rotation of the handle 9 causes the hones to rotate and inasmuch as the springs 14 and 15 tend to force the hones towards each other they engage the edges of the razor blades and as they rotate wipe the edges with a circular movement that tends to produce an extremely keen edge.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a safety razor blade sharpener, a pair of complementary casing members, clamp elements carried thereby arranged to secure a razor blade, sharpening elements rotatably mounted within said casing members at opposite sides of said razor blade and clamp elements, said sharpening elements being disposed about a common axis traversing the center of the razor blade and engageable with the edges of said razor blade, and handle means connected with said sharpening elements for rotating the same and extending from one of said casing members.

2. In a safety razor blade sharpener, a pair of clamp elements arranged to secure a razor blade therebetween, a pair of revoluble sharpening elements arranged at opposite sides of said razor blade and clamp elements, said sharpening elements being disposed about a common axis traversing the center of the razor blade and engageable with the edges of said razor blade, a casing enclosing said clamps, razor blade and sharpening elements and means for actuating said sharpening elements.

3. In a safety razor blade sharpener, a pair of

clamp elements arranged to secure a razor blade therebetween, a pair of revolute sharpening elements arranged at opposite sides of said razor blade and clamp elements, said sharpening elements being disposed about a common axis traversing the center of the razor blade and engageable with the edges of said razor blade, a casing enclosing said clamps, razor blade and sharpening element, shaft means carried by said casing and clamps for revolutely supporting said sharpening elements, and a handle therefor protruding from said casing for actuating the shafts and sharpening elements.

5 10 15 20 25 30 35 40 45 50 55 60 65 70 75 80 85 90 95 100 105 110 115 120 125 130 135 140 145 150

4. In a safety razor blade sharpener, a pair of clamp elements arranged to secure a razor blade therebetween, a pair of revolute sharpening elements arranged to engage the edges of said razor blade but having a position clear thereof, a split casing enclosing said clamps, razor and sharpening elements, a clasp for securing the casing in a closed position, a handle for rotating said sharpening elements, said handle engageable with said release clasp to release the same when said sharpening elements are clear of said razor blade.

5. In a safety razor blade sharpener, a pair of complementary casing members, a pair of clamp elements carried thereby arranged to receive a razor blade, coacting severable shafts supported by each of said casing members and its clamp element, rotatable sharpening elements supported from said shafts within each of said casing members and engageable with the edges of a razor blade held by said clamp elements, and means for rotating the shafts and sharpening elements.

6. In a safety razor blade sharpener, a pair of complementary casing members, a pair of clamp elements carried thereby arranged to receive a razor blade, coacting severable shafts supported by each of said casing members and its clamp element, means for operating said shafts, a spring arm connected to each shaft within the corresponding casing, and a hone mounted at the extended end of each spring arm and engageable with the edges of a razor blade held by said clamp elements upon operation of said shafts.

7. In a safety razor blade sharpener, a pair of complementary casing members, hinge and clasp means joining said casing members, a movable clamp element carried by one casing member, a fixed clamp element carried by the other casing member, coacting shafts journaled in said casing and separable with said clamp elements, sharpening members connected with said shafts and engageable upon rotation of said shafts with the edges of a razor blade held by said clamp elements and means for rotating said shafts and sharpening members.

8. In a safety razor blade sharpener, a pair of complementary casing members, hinge and clasp

60 65 70 75 80 85 90 95 100 105 110 115 120 125 130 135 140 145 150

means joining said casing members, a movable clamp element carried by one casing member, a fixed clamp element carried by the other casing member, coacting shafts journaled in said casing and separable with said clamp elements, 80 means for rotating said shafts, a spring arm connected with each shaft within the corresponding casing, and a hone supported at the extremity of each spring arm arranged to engage the edges of a razor blade held by said clamp elements 85 upon rotation of said shafts.

9. In a safety razor blade sharpener, a pair of cupped complementary casing members, hinge and clasp means joining said casing members, razor blade clamp bars bridging the open or contiguous sides of said casing members, adapted to receive a razor blade, a shaft carried by each clamp bar and its casing member, clutch means joining said shafts when said casing members are in complementary relation, sharpening members supported from said shafts and arranged to engage the edges of a razor blade held by said clamp bars and means for operating said shafts and sharpening members.

10. In a safety razor blade sharpener, a pair of cupped complementary casing members, hinge and clasp means joining said casing members, razor blade clamp bars bridging the open or contiguous sides of said casing members, adapted to receive a razor blade, a shaft carried by each 105 clamp bar and its casing member, clutch means joining said shafts when said casing members are in complementary relation, a spring arm joined to each shaft, a hone mounted at the extremity of each spring arm arranged to engage 110 the edges of a razor blade held by said clamp bars and means for operating the shafts and hones.

11. In a safety razor blade sharpener, a pair of cupped complementary casing members, hinge and clasp means joining said casing members, 115 razor blade clamp bars bridging the open or contiguous sides of said casing members, adapted to receive a razor blade, a shaft carried by each clamp bar and its casing member, clutch means joining said shafts when said casing members 120 are in complementary relation, one of said clamp bars and its shaft being axially shiftable, yieldable means tending to hold the same in an extended relation with their casing, whereby said clamp bar may give to accommodate a razor blade 125 positioned on the other clamp bar and whereby said clutch means tends to occupy an interlocking condition, sharpening members supported from said shafts and arranged to engage the edges of a razor blade held by said clamp bars 130 and means for operating said shafts and sharpening members.
